UNITED STATES PATENT OFFICE

96,208

DESIGN FOR A WATCH

Joseph E. Sunshine, Chicago, Ill.

Application November 19, 1934, Serial No. 54,072

Term of patent 3½ years

To all whom it may concern:

Be it known that I, Joseph E. Sunshine, a citizen of the United States, residing at Chicago, in the county of Cook, and State of Illinois, have invented a new, original, and ornamental Design for a Watch, of which the following is a specification, reference being had to the accompanying drawing, forming a part hereof, in which—

Figure 1 is a face view of a watch showing my new design;

Figure 2 is a back view thereof; and

Figure 3 is an edge view taken from the right-hand side of Figure 1.

The novel watch is an article intended to be carried by men in a trouser pocket, and by ladies in a hand bag or purse. The watch is in the form of a relatively thin circular disk and the only parts slightly protruding from its surface are the lens and the winding stem, the balance of the formation being that of a disk with a flat periphery.

I claim:

The ornamental design for a watch as shown and described.

In testimony whereof I affix my signature.

JOSEPH E. SUNSHINE.
